UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,255,180.

Specification of Letters Patent. Patented Feb. 5, 1918.

Application filed April 26, 1917. Serial No. 164,635.

To all whom it may concern:

Be it known that I, CHARLES W. KECKLER, a citizen of the United States, residing at Newark, in the county of Essex and State 5 of New Jersey, have invented certain new and useful Improvements in Telephone Systems, of which the following is a full, clear, concise, and exact description.

This invention relates to telephone systems, 10 and more particularly to such systems of the central energy type, its object being the provision of improved means for testing the busy or idle connection of a called telephone line.

15 In accordance with the feature of this invention there is associated with a plurality of link circuits employed for connecting together telephone lines, a relay in a Wheatstone bridge circuit common to the link circuits, which is responsive to the engagement of a link circuit with the terminal of a busy line to operatively associate a source of tone signaling current with an operator's receiver.

20 This invention is illustrated in the accompanying drawing in which all apparatus is shown in its normal condition.

In the drawing there is shown a telephone line A, extending from a subscriber's station 25 to a central office, where it terminates in a plurality of jacks 16 and 26. At the central office there is a plurality of cord circuits B and C for connecting together telephone lines, it being understood, of course, that a 30 plurality of lines, similar to line A, terminate at the central office. An operator's telephone set shown in the lower dotted rectangle D is common to the cord circuits, and a Wheatstone bridge circuit shown in the 35 upper dotted rectangle is also common to the cord circuits. Only three arms 5, 6 and 7 of the Wheatstone bridge circuit are normally connected therewith. A fourth arm is associated with the cord circuits.

40 Two relays 8 and 9 are permanently connected across the Wheatstone bridge circuit, relay 8 being normally energized by current over a path from battery through the bridge arm 5, windings of relays 8 and 9, bridge 45 arm 7, (the bridge arm 6 being connected in parallel with the windings 8 and 9 and the bridge arm 7), and the contact of the key 10 to ground. The contact of relay 8, is therefore, normally open. Relay 9 is marginal 50 and does not attract its armature when in-

cluded in the circuit just traced. Therefore, its contact is normally open. The contact of relay 8, when closed, establishes an operating circuit including a winding 11 of an induction coil 12, a second winding 13 of 60 which is in circuit with receiver 14 of the operator's telephone set. The closure of this contact sends an impulse of current from battery through winding 11 of the induction coil 12, whereupon a tone is produced in the 65 operator's receiver. The closure of the contact of the relay 8 may, therefore, be considered as operatively associating a source of tone signaling current with the receiver 14 of the operator's telephone set. 70

The fourth arm of the bridge may have two different values of resistance under differing conditions. If the plug 15 of cord circuit B be inserted into the jack 16 of line A, the fourth arm of the bridge will then be 75 made up of the left-hand winding of relay 17^b, and the right-hand winding of the cut-off relay 18. The left-hand winding of relay 17 is of high resistance, while the right-hand winding is of low resistance. Therefore 80 relay 17 does not operate when its left-hand winding only is in circuit, but does operate when its right-hand winding is included in circuit. When the fourth arm of the bridge, consisting of the left-hand winding of relay 17^b and the right-hand winding 85 of cut-off relay 18, is connected to the bridge, the marginal relay 9 operates, thereupon completing an operating circuit through the right-hand winding of relay 90 17^b, which then operates and locks up through its right-hand alternate contact. In operating, relay 17^b disconnects the Wheatstone bridge circuit from cord circuit B and also disconnects the fourth arm from 95 the bridge, restoring the bridge to normal. With the plug the cord circuit B connected with a jack of line A, cut-off relay is operated to connect the sleeve terminals of the jacks to the ring terminal thereof, so that 100 the potential of these sleeve contacts is raised.

If the operator, in testing the condition of line A, touches the tip contact of plug 15 of cord circuit C to the sleeve terminal of jack 105 26 of line A, a fourth arm for the bridge will be established, which includes the winding of relay 27^b, the winding 28^b of repeating coil 29^b and the left-hand winding of relay 17^c. With this fourth arm connected to the bridge, 110

the resistance in the various arms is then such that there is no difference of potential at the terminals of relays 8 and 9. Relay 8 thereupon releases its armature, completing the hereinbefore mentioned operating circuit, including the winding 11 of induction coil, whereupon a tone is produced in the operator's receiver 14, indicating to the operator that line A is busy.

10 The removal of the plug 15 of cord circuit B from the jack 16 causes the deenergization of relay 17 and cut-off relay 18, whereupon all apparatus is restored to normal position. Cut-off relay 18 is differentially wound and does not attract its armature when the receiver of the subscriber's station is removed from the switchhook to initiate a call, but line relay 19 is then operated. The operator's telephone set may be 20 connected with either cord circuit by the actuation of the proper listening key 30.

What is claimed is:

1. A telephone system comprising a telephone line terminating in a plurality of sets 25 of terminals, a plurality of link circuits, one being connected with one set of terminals, an operator's telephone set, a source of tone signaling current, a Wheatstone bridge circuit having three arms common to the link 30 circuits, a fourth arm for the bridge connected therewith upon engagement of another link circuit with a terminal of another set, and means in the bridge responsive to the connection of the fourth arm therewith 35 to operatively associate the source of tone signaling current with the receiver of the operator's telephone set.

2. A telephone system comprising a telephone line terminating in a plurality of sets 40 of terminals, a plurality of link circuits, one being connected with one set of terminals, an operator's telephone set, a source of tone signaling current, a Wheatstone bridge circuit having three arms common to the link 45 circuits, a fourth arm for the bridge connected therewith upon engagement of another link circuit with a terminal of another set, and a relay in the bridge responsive to the connection of the fourth arm therewith 50 to operatively associate the source of tone signaling current with the receiver of the operator's telephone set.

3. A telephone system comprising a telephone line terminating in a plurality of sets 55 of terminals, a plurality of link circuits, one being connected with one set of terminals, an operator's telephone set, a source of tone signaling current, a Wheatstone bridge circuit common to the link circuits, means for altering the electrical condition 60 of the bridge upon the engagement of another link circuit with a terminal of another set, and means in the bridge responsive to the altered condition thereof 65 to operatively associate the source of tone signaling cur-

rent with the receiver of the operator's telephone set.

4. A telephone system comprising a telephone line terminating in a plurality of sets of terminals, a plurality of link circuits, 70 one being connected with one set of terminals, an operator's telephone set, a source of tone signaling current, a Wheatstone bridge circuit common to the link circuits, means for altering the electrical condition of the 75 bridge upon the engagement of another link circuit with a terminal of another set, and a relay in the bridge responsive to the altered condition thereof to operatively associate the source of tone signaling current 80 with the receiver of the operator's telephone set.

5. A telephone system comprising a telephone line terminating in a plurality of sets of terminals, a plurality of link circuits, 85 one being connected with one set of terminals, an induction coil having two windings, a responsive device in circuit with one winding, a Wheatstone bridge circuit having three arms common to the link circuits, a 90 fourth arm for the bridge connected therewith upon engagement of another link circuit with a terminal of another set, and means in the bridge responsive to the connection of the fourth arm therewith to complete 95 an operating circuit including the other winding of the induction coil.

6. A telephone system comprising a telephone line terminating in a plurality of sets of terminals, a plurality of link circuits, 100 one being connected with one set of terminals, an induction coil having two windings, a receiver in circuit with one winding, a Wheatstone bridge circuit having three arms common to the link circuits, a fourth arm 105 for the bridge connected therewith upon engagement of another link circuit with a terminal of another set, and a relay in the bridge responsive to the connection of the fourth arm therewith to complete 110 an operating circuit including the other winding of the induction coil.

7. A telephone system comprising a telephone line terminating in a plurality of sets of terminals, a plurality of link circuits, 115 one being connected with one set of terminals, an induction coil having two windings, a responsive device in circuit with one winding, a Wheatstone bridge circuit common to the link circuits, means for altering the electrical condition of the bridge upon the engagement of another link circuit with a terminal of another set, and means in the bridge responsive to the altered condition thereof to complete 120 an operating circuit including the other winding of the induction coil.

8. A telephone system comprising a telephone line terminating in a plurality of sets of terminals, a plurality of link circuits, one 125

- being connected with one set of terminals, an induction coil having two windings, a receiver in circuit with one winding, a Wheatstone bridge circuit common to the link circuits, means for altering the electrical condition of the bridge upon the engagement of another link circuit with a terminal of another set, and a relay in the bridge responsive to the altered condition thereof 5 to complete an operating circuit including the other winding of the induction coil.
9. A telephone system comprising a plurality of telephone lines, a plurality of link circuits for interconnecting the lines, a 15 Wheatstone bridge circuit having three arms common to the link circuits, a fourth arm for the bridge connected therewith upon connection of one of the link circuits with one of the telephone lines, a switching device in 20 the bridge responsive to the connection of the fourth arm therewith, and means in the engaged link circuit operating upon response of the switching device to disconnect the bridge from the engaged link circuit.
- 25 10. A telephone system comprising a plurality of telephone lines, a plurality of link circuits for interconnecting the lines, a Wheatstone bridge circuit having three arms common to the link circuits, a fourth arm 30 for the bridge connected therewith upon connection of one of the link circuits with one of the telephone lines, a switching device in the bridge responsive to the connection of the fourth arm therewith, and a relay 35 in the engaged link circuit operating upon response of the switching device to disconnect the fourth arm from the bridge.
11. A telephone system comprising a plurality of telephone lines, a plurality of link 40 circuits for interconnecting the lines, a Wheatstone bridge circuit common to and normally connected with the link circuits, means for altering the electrical condition 45 of the bridge upon connection of one of the link circuits with one of the lines, a switching device in the bridge responsive to the altered condition of the bridge, and means in the engaged link circuit operating upon 50 response of the switching device to disconnect the bridge from the engaged link circuit.
12. A telephone system comprising a plurality of telephone lines, a plurality of link circuits for interconnecting the lines, a 55 Wheatstone bridge circuit common to and normally connected with the link circuits, means for altering the electrical condition 60 of the bridge upon connection of one of the link circuits with one of the lines, a switching device in the bridge responsive to the altered condition of the bridge, and a relay

in the engaged link circuit operating upon response of the switching device to disconnect the bridge from the engaged link circuit.

65

13. A telephone system comprising a plurality of telephone lines, each terminating in a plurality of sets of terminals, a plurality of link circuits for interconnecting the lines, an operator's telephone set, a 70 Wheatstone bridge circuit common to and normally connected with the link circuits, a source of tone signaling current, means for altering the electrical condition of the bridge upon connection of one of the link 75 circuits with one set of terminals of a telephone line, a switching device in the bridge responsive to the altered condition thereof, a relay in the engaged link circuit operating upon response of the switching device to 80 disconnect the bridge from the engaged link circuit and to restore the bridge to normal condition, means for again altering the electrical condition of the bridge upon the subsequent engagement of another link circuit 85 with a terminal of another set associated with the engaged line, and means in the bridge responsive to the last mentioned altered condition thereof to operatively associate the source of tone signaling current 90 and the receiver of the operator's telephone set.

95

14. A telephone system comprising a plurality of telephone lines, each terminating in a plurality of sets of terminals, a plurality of link circuits for interconnecting the lines, an operator's telephone set, a Wheatstone bridge circuit normally connected to the link circuits and having three arms common thereto, a source of tone signaling current, a fourth arm for the bridge connected therewith upon connection of one of the link circuits with one set of terminals of a telephone line, a relay in the bridge responsive to the connection of the fourth arm thereto, 100 a relay in the engaged link circuit operating upon response of the bridge relay to disconnect the bridge from the engaged link circuit and the fourth arm from the bridge, another fourth arm for the bridge connected 105 therewith upon the subsequent engagement of another link circuit with a terminal of another set associated with the engaged line, and another relay in the bridge responsive to the connection of the second mentioned 110 fourth arm thereto to operatively associate the source of tone signaling current and the receiver of the operator's telephone set.

100

115

In witness whereof, I hereunto subscribe my name this 25th day of April, A. D. 1917. 120

CHARLES W. KECKLER.
